UNITED STATES PATENT OFFICE.

OSCAR MILTON HATCHER, OF MANKATO, MINNESOTA.

HIGHWAY MARKER.

Application filed July 9, 1923. Serial No. 650,338.

My invention relates to improvements in highway markers.

The marking of highways, trails and roads is ordinarily accomplished by painting names, numbers, symbols or insignia, or combinations thereof, in appropriate manner to suit each location on posts, fences, bridges, culverts and rocks along the various ways or by constructing special unitary signs for given places and affixing the same to specially provided standards or other supports that may be handy. Signs painted on the various objects along a highway are obliterated by the elements within relatively short periods and the renewal thereof is attended with considerable labor and material costs. Cast and sheet metal signs, though inexpensive in maintenance, are limited owing to the high cost of special patterns and dies needed in meeting the numerous differing requirements and, also, because of the labor expended in segregating, transporting and properly locating the signs.

Broadly, the object of my present invention is to supply a simple and durable marker for a highway system, the same being designed to serve as a legible guide for travelers and adapted to be quickly and easily assembled from standard parts into unitary form suitable to available supporting means at any given location.

Another object is to provide a highway marker, the cost of production like the cost of erection and maintenance thereof being relatively low.

A further and more specific object is to supply a composite metallic marker of this kind including a body member adapted to be readily secured to an anchoring element in various angular positions with respect thereto, whereby said body member may be suitably displayed in various positions of said anchoring element.

Another object is to supply sign units, couplers for joining the same in various relative positions and means for variously anchoring the assembled marker structure.

With the foregoing and other objects in view, which will appear in the following description, the invention resides in the novel combination and arrangement of parts and in the details of construction hereinafter described and claimed.

In the drawings, Fig. 1 is an elevational view of a highway marker embodying my

invention; Fig. 2 is a sectional view taken on the line 2-2 of Fig. 1; Figs. 3 and 4 are perspective views, in detail, illustrating the complementary parts of an anchoring element; Figs. 5, 6, 7, 8 and 9 are elevational views of markers, the same showing sign members variously assembled and mounted; Figs. 10 and 11 are perspective views, in detail, illustrating complementary members of the coupler used in securing one sign member to another and Fig. 12 is an elevational view illustrating an alternate form of sign member.

The sign members A, anchoring elements or brackets B and couplers C, preferably formed of cast metal, are assembled in various combinations to suit different locations and supporting objects. Each sign member A includes a marked panel 9 having a perimetrical flange or rim 10 framing the panel at either side thereof. In this flange are opposed notches 11, the same being located at the top, bottom and sides of the sign member and at positions therebetween, if desired. Each anchoring element or bracket B comprises complementary parts, one consisting of a shank 12 formed with an attaching flange 13 at one side thereof and with a head 14 at the opposite side, the other part consisting of a plate 15 and a head 16 thereon. Said complementary parts of an anchoring element B fit together as shown, grooves 14^a, 16^a being formed in the heads 14, 16 to receive the opposite edges of a flange 10 on a sign member A. Lugs 14^b, 16^b interrupting said grooves 14^a, 16^a medially thereof fit in opposed notches 11 in a flange 10. A sign member A embraced by the complementary parts of an anchoring bracket B and interlocked therewith is held in place between said parts by means of clamping bolts 17 reaching through registering apertures 12^a, 15^a in the shank 12 and plate 15. The anchoring element B is secured to either side, top or bottom of a supporting object by means of screws 18 or bolts reaching through apertures 19 in the flange 13 and into the object. With the several opposed notches 11 in the flange 10 of a sign member A, it will be observed that said member may be displayed in upright position in numerous positions of its anchoring bracket.

The coupler C for attaching one sign member A to another consists of identical complementary parts (Figs. 10, 11) each

comprising a shank 20 with heads 21 at the sides thereof. These heads 21 are formed with grooves 22 to receive the edges of flanges 10 of sign members A and said 5 grooves are interrupted medially by lugs 23, which fit in the notches 11 in said flanges. Bolts 24 reaching through registering openings 25 in the shanks 20 of the coupler parts clamp said parts together in 10 embracing, interlocking engagement with sign members A. The adaptability of the coupler C for various selective applications to sign members A permits of numerous arrangements some of which are shown in the 15 drawings.

In providing markers for a given highway system, the manufacturer constructs a number of anchoring brackets B, couplers C and sign members A, the latter bearing various 20 markings to meet different requirements in different combinations. A sign erector, equipped with a stock of these parts, secures an anchoring bracket B to any convenient support at a location to be marked. 25 Regardless of the position of the bracket B, the appropriate sign member A may be readily secured thereto and displayed in proper upright position. Should a highway at any given location require multiple markings, the necessary sign members may be individually attached to the supporting object by means of separate brackets B or assembled for anchorage on a single bracket by means of couplers C. Since the sign 30 members A may occupy various angular positions with respect to their connecting couplers C it will be understood that one or more companion sign members A may be displayed in upright position at various locations relative to a main sign member 40.

From the foregoing, it will be understood that the construction and use of my improved marker is attended with low manufacturing, erection and maintenance costs.

Changes in the specific form of my invention, as herein disclosed, may be made within the scope of what is claimed without departing from the spirit of my invention.

Having described my invention, what I claim as new and desire to protect by Letters Patent is:

1. In a highway marker, sign members, each member having a flange at the margin thereof formed with notches therein, an anchoring element for attachment to a support, said element comprising complementary parts for interlockingly embracing different marginal portions of one of the sign members, and a coupler comprising complementary opposed parts for interlockingly embracing different marginal portions of the member held by said element and different marginal portions of another sign member.

2. In a highway marker, two sign mem-

bers, an anchoring element for attachment to a support, said element comprising complementary parts for gripping different marginal portions of one of the sign members, and a coupler comprising dual complementary parts for gripping different marginal portions of both members, the margins of said sign members being formed for interlocking coaction with said anchoring element and coupler.

3. In a highway marker, two sign members, means for anchoring one of said members to a support, a coupler comprising dual complementary parts for gripping different marginal portions of both members, the margins of said members being formed to interlockingly co-act with said parts of said coupler in various relative positions.

4. A composite highway marker including a body and companion sign members, an anchoring element, said body member having a marginal connection with said anchoring element, said connection being adjustable to permit of the upright positioning of said body member in various positions of said anchoring member and couplers to secure said companion sign members to said body member, said couplers having adjustable marginal connections with said body and companion members to permit of the location of the latter in upright positions and in various angular relations with respect to said body member.

5. In a highway marker, a plurality of sign members, an anchoring element for attachment to a support, either of said members being variously applicable to the anchoring element to permit of proper presentation thereof in various positions of said element and connecting means co-operating with the member carried by the anchoring element and with the companion sign members to secure the latter in various angular relations with respect to the former and to provide for the proper presentation of said companion members in their various positions.

6. In a highway marker, a body, a perimetrical flange on said body formed with opposed notches therein and an anchoring element for attachment to a support, said element comprising complementary parts for embracing different marginal portions of the body, said parts being grooved to receive said flange and formed with lugs thereon for engagement with certain of said notches.

7. In a highway marker, a body, a perimetrical flange on said body formed with opposed notches therein and an anchoring element for attachment to a support, said element comprising complementary parts for embracing different marginal portions of the body, one of said parts being grooved to receive said flange and one of said parts

being formed with a lug for engagement, severally, with said notches.

8. In a highway marker, a body, a perimetrical flange on said body formed with notches therein, and an anchoring element for attachment to a support, said element comprising complementary parts for em-

bracing different marginal portions of the body, one of said parts being formed to receive said flange and also formed with a lug for engagement, severally, with said notches.

In testimony whereof, I have signed my name to this specification.

OSCAR MILTON HATCHER.
